UNITED STATES PATENT OFFICE

THOMAS L. PARKER, OF CHICAGO, ILLINOIS, ASSIGNOR TO THE STANDARD ELECTRIC MANUFACTURING CO., OF CHICAGO, ILLINOIS, A CORPORATION OF ILLINOIS

SWITCH BUTTON

Original application filed December 27, 1926, Serial No. 157,184. Divided and this application filed March 1, 1928. Serial No. 258,196.

This invention relates to improvements in switch buttons and more particularly to buttons of the character which are used in connection with rotary snap switches.

- 5 An object of applicant's invention is the production of a switch button which may be quickly assembled and attached to the stem of a rotary snap switch thereby effecting a great saving in time.
- 10 Another object of applicant's invention is the production of a button for a rotary snap switch which will resiliently secure the cover for the movable parts in place.

Another object of applicant's invention is 15 the production of a construction which will permit the use for switch buttons of materials, such as porcelain and others in which metals are not readily molded or cast.

A further object of applicant's invention 20 is the provision of a switch button of the above type including in its construction, preferably a non-conductive body having a bore and sleeve positioned within the bore with a coil spring surrounding the same together with improved means seated within the outer open end of the bore cooperating with the sleeve whereby to restrain displacement of the sleeve.

A further object of applicant's invention is 25 the production of a switch button of low cost, durable, of a small number of parts and highly satisfactory for its intended purpose.

Many other objects and advantages of the construction herein shown and described will 30 be obvious to those skilled in the art from the disclosure herein given.

To this end my invention consists in the novel construction, arrangement and combination of parts herein shown and described, 35 and more particularly pointed out in the claims.

In the drawings, wherein like reference characters indicate like or corresponding parts:

Fig. 1 is an end elevation of the device applied to a rotary type of electrical switch;

Fig. 2 is an end elevation of the switch button;

Fig. 3 is a vertical section of the same; and

Fig. 4 is a section taken on line 4—4 of Fig. 3.

Referring to the drawing, I have illustrated in Fig. 1 my improved switch button applied to a snap switch generally indicated by the reference character 1. At 1' is shown a cover for the inner parts of the switch. At 2 is shown my improved switch button which is preferably formed with wings 3. However, same may be of any suitable contour such as round, oblong, etc. The switch button 2 is formed of a base 4 with a bore 5 therein. The bore 5 may be of any contour such that the head 6 on the sleeve 7 is constrained to rotate therewith. However, same may move longitudinally in and out of bore 5. The term "sleeve" is here used to include a solid or partially solid construction. The sleeve 7 except for the head 6 is of smaller diameter than the bore 5 which provides space for the accommodation of a spring 8 which clips over the sleeve 7 and engages the head thereof. The outer end of bore 5 is preferably enlarged as shown at 18. In the enlarged portion is positioned a combined sleeve supporting spring retaining member 9 which preferably engages the shoulder 10. Thus, holding the sleeve 7 in place and maintaining preferably a slight tension on the spring 8. The member 9 is 60 preferably disc-shaped and has an annular groove 11 in its periphery which is positioned opposite the annular groove 12 on the inner wall of the enlarged portion 18. The combined sleeve supporting spring retaining member 9 is held in the bore 18 by means of the resilient member 13 which is so formed that same will spring outward into the groove 11. It is thus seen that the head 6 of the 70 sleeve 7 is resiliently urged into the bore 5. The sleeve 7 may have an internal bore 14 in the end thereof which accommodates a stem 15. The member 13 is shown in position in Fig. 4. It is thus seen that a highly efficient 75 device is provided satisfactory for its intended purpose. This application constitutes a division of my copending application, Serial No. 157,184, filed December 27, 1926.

Having thus described my invention; it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

- 10 1. A device of the character described including a body formed with a bore having an enlarged end formed with an annular recess, a sleeve removably arranged in the bore, a closure plate mounted on the sleeve and formed with an annular recess in its periphery to be arranged in opposed relation with the recess in the bore, and a split ring arranged in the recesses to retain said plate in the enlarged end of the bore.
- 15 2. A device of the character described, a body having a bore, a circumferential recess in said bore, a sleeve having an enlarged portion movably arranged in said bore and constrained to rotate therewith, a closure plate embracing said sleeve, a circumferential recess on said closure plate, means in said recesses for retaining said plate in said bore, and resilient means engaging said plate and the enlarged portion of said sleeve.
- 20 3. A device of the character described, a body having a bore with an enlarged end, a circumferential recess in said enlarged end, a sleeve having an enlarged portion movably arranged in said bore and constrained to rotate with said body, a closure plate fitting over said sleeve, a circumferential recess on said closure plate, a split ring in said recesses for retaining said plate in position, and resilient means between said plate and said enlarged portion of said sleeve.
- 25 4. In a device of the character described, a body having a bore closed at one end, the open end of said bore being enlarged and cylindrical and having an annular recess therein, a sleeve mounted in said bore, a head on the inner end of said sleeve constraining the sleeve to rotate with the body, a closure plate mounted on the sleeve said plate having an annular recess in its outer periphery arranged in opposed relation with the recess in the bore, and a split ring arranged in the recesses to retain said plate in the enlarged end of the bore.
- 30 5. In testimony whereof, I have hereunto signed my name.

THOMAS L. PARKER.
